SPRINKLER

Lloyd B. Smith, 824 N. 31st St., Birmingham, Ala.

Filed Mar. 26, 1958, Ser. No. 724,053

20 Claims. (Cl. 239—239)

This invention relates to a sprinkler and more particularly to a wave type sprinkler adapted for sprinkling lawns and the like.

An object of my invention is to provide a sprinkler of the character designated in which the water is distributed evenly over the entire sprinkler pattern, whereby there is no excess of water adjacent the outer edge of the pattern.

Another object of my invention is to provide a sprinkler of the character designated which shall embody a water motor having a vane mounted for pivotal movement and a sprinkler conduit connected non-rotatably to the vane, together with pressure release means for bypassing water to the sprinkler conduit, whereby the bypassed water does not act upon the vane to further increase the speed of oscillation thereof, thus providing a water motor which oscillates at a predetermined speed.

A further object of my invention is to provide a wave type water sprinkler of the character designated in which the angular pivotal movement of the sprinkler is adjustable whereby the sprinkler pattern may be varied.

A still further object of my invention is to provide a sprinkler of the character designated which shall be simple of construction, economical of manufacture and one which is trouble free in operation and requires a minimum of maintenance.

Heretofore in the art to which my invention relates, various types of wave type sprinklers have been proposed. However, such sprinklers with which I am familiar are unsatisfactory due to the fact that the water motor is actuated by water which does not pass through the sprinkler conduit. That is, the water which actuates the water motor is discharged from the water motor without entering the sprinkler conduit. Also, wave type sprinklers heretofore employed have required a complicated assembly of parts which requires considerable maintenance to maintain the same in trouble free operation. Furthermore, no effective means has been provided to regulate the speed at which the sprinkler conduit oscillates.

Briefly, my improved sprinkler comprises a water motor having a vane mounted for pivotal movement in a casing and including a water inlet and a water outlet. A sprinkler conduit is connected to the vane of the motor and the water outlet thereof and is adapted to oscillate therewith. To regulate the speed at which the vane and the sprinkler conduit oscillate, I provide pressure release means to bypass water to the sprinkler conduit when the water pressure exceeds a predetermined amount.

Sprinklers embodying features of my invention are illustrated in the accompanying drawings, forming a part of this application, in which:

Fig. 1 is a vertical sectional view, partly broken away, showing one form of the sprinkler;

Fig. 2 is an enlarged view taken generally along the line 2—2 of Fig. 1, the housing and wall between the two casings being omitted for the sake of clarity;

2

Fig. 3 is an enlarged view taken generally along the line 3—3 of Fig. 1;

Fig. 4 is an exploded view showing the vane and the mechanism for introducing water into the water motor casing adjacent opposite sides of the vane;

Fig. 5 is an enlarged fragmental view, partly broken away and in section, showing the pressure release means associated with the apparatus shown in Figs. 1—4;

Fig. 6 is a perspective view showing the valve of the pressure release means shown in Fig. 5;

Fig. 7 is a view taken generally along the line 7—7 of Fig. 8 and showing a modified form of sprinkler;

Fig. 8 is a sectional view taken generally along the line 8—8 of Fig. 7;

Fig. 9 is a perspective view showing the valve plate member for regulating the flow of water to the water motor and the pressure release means for the sprinkler shown in Figs. 7 and 8;

Fig. 10 is a side elevational view, partly broken away and in section, showing another form of sprinkler;

Fig. 11 is an enlarged fragmental view taken generally along the line 11—11 of Fig. 10;

Fig. 12 is a perspective view showing the water motor vane for the sprinkler shown in Figs. 10 and 11;

Fig. 13 is a side elevational view, partly broken away and in section, showing a further modified form of my invention;

Fig. 14 is an enlarged sectional view taken generally along the line 14—14 of Fig. 13;

Fig. 15 is a side elevational view, broken away and in section, showing a still further modified form of my invention; and,

Fig. 16 is a sectional view taken generally along the line 16—16 of Fig. 15;

Referring now to the drawings for a better understanding of my invention, and more particularly to Figs. 1—6, I show a housing 10 for the sprinkler which may be mounted on a suitable stand, not shown. The housing 10 is divided by a wall 11 to provide a water motor casing 12 and a second casing 13 for supplying water to the water motor casing. Water is supplied to the casing 13 by a suitable hose connection 14.

Extending through the water motor casing 12 and adapted for pivotal movement relative to the rear wall 16 of the housing 10 and the wall 11 is a tubular member 16 having elongated openings 17 and 18 at opposite sides thereof, as shown in Figs. 1 and 3. Telescoping within the tubular member 16 is a sprinkler conduit 19 having elongated openings 21 and 22 therein which are in register with the openings 17 and 18 in the tubular member 16. The tubular member 16 and the conduit 19 are secured non-rotatably to each other by suitable means, such as by a pin 23. While I show the conduit 19 as being separate from the tubular member 16, it will be apparent that the members 16 and 19 could be formed as an integral member. The conduit 19 extends outwardly of the housing 10 and is provided with a plurality of sprinkling orifices 24 therein for discharging water as the conduit is oscillated.

Secured to the tubular member 16 and adapted for pivotal movement therewith is a water motor vane 26 which slidably engages the inner surface of the casing 12, as shown in Fig. 1. Preferably, the periphery of the vane 26 is tapered to provide a relatively thin outer contact surface 27 which wipes against the inner surface of the water motor casing 12 to form an effective seal therewith.

Telescoping within the conduit 19 is a tubular member 28 having a partition 29 therein. An opening 31 is provided in the partition 29 for receiving a pressure relief valve 32, as shown in Figs. 5 and 6. The pressure relief valve 32 comprises a disc-like member 33 which is

disposed to engage the partition 29, as shown in Fig. 5, whereby it is adapted to move away from the partition 29 when the pressure in the tubular member 28 exceeds a predetermined amount. The valve member 32 is urged into engagement with the partition 29 by a suitable spring 34 which is interposed between a spring abutment 36 carried by the valve member 32 and the adjacent side of the partition 29. It will thus be seen that as the pressure within the tubular member 28 increases to a point that it overcomes the force exerted by the spring 34, the 10 disc-like member 33 is moved outwardly from the partition member 29 to allow water to flow through the opening 31.

Oppositely disposed openings 37 and 38 are provided in the tubular member 28 at opposite sides of the partition 29 whereby they are in alignment with the elongated openings 21 and 22 in the conduit 19. It will thus be seen that with the tubular member 28 in the position shown in Fig. 3, the water entering the tubular member passes through the openings 38, 22 and 18 into the casing 12 adjacent one side of the vane 26. Any water on the opposite side of the vane 26 then flows into the tubular member 28 through the openings 17, 21 and 37 at the opposite side of the partition 29 whereby the water is discharged through the conduit 19 and sprinkler orifices 24. The tubular member 28 is also provided with oppositely disposed openings 39 and 41 which are positioned at opposite sides of the partition 29. As shown in Fig. 3, the openings 39 and 41 are spaced angularly from the openings 37 and 38 whereby upon rotation of the tubular member 28 in a counter-clockwise direction from the position shown in Fig. 3, the openings 39 and 41 move in to register with the openings 21 and 22 in the conduit 19. In this latter position, the water entering the inlet end of the tubular member 28 passes through the openings 39, 21 and 17 into the adjacent side of the casing 12. Any water in the casing 12 at the opposite side of the vane 26 passes through the openings 18, 22 and 41 into the tubular member 28 and thence outwardly through the conduit 19 to the sprinkler orifices 24. It will thus be seen that as the vane 26 and the members 19 and 16 oscillate, the openings 17—21 and 18—22 move into register alternately with the openings 37 and 39 and 38 and 41, respectively, whereby the water is introduced alternately at opposite sides of vane 26. In view of the fact that the openings 37 and 41 move in to register with the openings 17—21 and 18—22 as the vane 26 is oscillated, the water is exhausted alternately through the openings 37 and 41 into the tubular member 28 and the conduit 19 where it is conveyed to the sprinkler orifices 24.

Mounted adjacent each side of the tubular member 16 within the casing 13 are outwardly extending members 42 and 43. Telescoping over the inlet end of the member 16 is a collar 44 having an outwardly projecting arm 46 which is in position to be engaged by the projections 42 and 43 as the vane 26 oscillates the tubular member 16. Secured to the outer end of the tubular member 28 and adapted for pivotal movement therewith is an outwardly projecting arm 47. Pivotal movement of the arm 47 is limited by adjustable stop members 48 and 49 which are carried by an actuating member 51. Connecting the outer ends of the arms 46 and 47 is a spring member 52 which urges the arms 46 and 47 in opposite directions when the pivotal connection between the arm 46 and the spring 52 passes dead-center of a line extending radially from the axial center of the tubular member 28 and the pivotal connection of the spring 52 to the arm 47. That is, with the arms 46 and 47 in the position shown in Fig. 2, water is introduced through the opening 38 to the casing 12 at the right side of the vane 26 whereupon the projection 43 engages the arm 46 and moves the same toward the left or in a clockwise direction. As the pivotal connection between the arm 46 and the spring 52 passes dead-center of a line extending radially from the axial center of the tubular member 28 and the pivotal con-

nection between the arm 47 and the spring 52, the spring 52 causes the arm 47 to move quickly toward the right and into engagement with the stop member 49. In the latter position, the water is introduced into the casing 12 through the opening 39 and discharged therefrom through the opening 41.

The actuating member 51 is provided with a control knob 53. Interposed between the control knob 53 and the housing 10, as shown in Fig. 1, is a compression spring 54 which urges the knob 53 outwardly of the housing 10. As shown in Fig. 4, the actuating member 51 carries a series of notches 56 which are in position to engage a stop member 57 to hold the actuating member 51 in selected position. To operate the actuating member 51, the knob 53 is pushed inwardly against the compression of spring 54 whereupon the notches move out of engagement with the stop 57 to permit free rotation of the actuating member 51. Upon moving the actuating member to the desired position, the knob 53 is released to return the actuating member in the desired locked position. With the actuating member 51 extending in a horizontal plane, as shown in Figs. 1 and 4, the sprinkling conduit 19 oscillates equal distances at each side of a vertical plane passing through the center of the conduit 19. Preferably, in this position, the conduit oscillates 45° at each side of the vertical plane passing through the axial center line of the conduit 19. To cause the conduit 19 to rotate a further angular distance toward either side, the control knob 53 is actuated to move the stops 48 and 49 in the proper direction. That is, if it is desired to oscillate the conduit 19 further toward the counter-clockwise direction, the control knob is pushed inwardly and turned in a counter-clockwise direction to reset the actuating member 51. On the other hand, if it is desired to oscillate the conduit 19 further in a clockwise direction, the control knob 53 is pushed inwardly and rotated in a clockwise direction to reset the actuating member 51. The stops 48 and 49 are thus positioned at selected angular positions whereby the angular movement of the sprinkling conduit 19 may be varied.

From the foregoing description, the operation of my improved sprinkler shown in Figs. 1-6 will be readily understood. The hose connection 14 is connected to a water supply hose and the knob 53 is set at the desired position to determine the angle of oscillation of the sprinkling conduit 19. With the tubular member 28 in the position shown in Fig. 3, water is introduced through the connection 14 into the casing 13 and thence through the inlet of the tubular member 28. The water then passes through the openings 38, 22 and 18 into the casing 12 adjacent the right side of the vane 26, as viewed in Fig. 3. The water at the other side of the vane 26 is then exhausted through the openings 17, 21 and 37 into the tubular member 28 and then through sprinkler conduit 19 to the orifices 24. As the water forces the vane 26 in a clockwise direction, as viewed in Fig. 3, the projection 43 engages the arm 46 and rotates the same in a clockwise direction. As the pivotal connection between the arm 46 and the spring 52 passes dead-center of a line extending radially from the axial center of the tubular member 28 through the connection of the arm 47 to the spring 52, the spring 52 urges the arm 47 quickly in a counterclockwise direction to position the openings 39 and 41 in register with the openings 17—21 and 18—22, respectively. In the latter position, the water enters the inlet end of the tubular member 28 and passes through the opening 39 into the casing 12 adjacent the left-hand side of the vane 26, as viewed in Fig. 3, thus causing the vane 26 to be oscillated in a counter-clockwise direction. Water at the opposite side of the vane 26 is then exhausted through the openings 18, 22 and 41 to the tubular member 28 and thence outwardly through the conduit 19 to the sprinkler orifices 24.

If it is desired to vary the angular pattern made by the sprinkler conduit 19, the knob 53 is compressed inward

and moved in the desired direction and then released to set the stops 48 and 49 in the correct angular positions relative to the arm 47.

Should the pressure of the water in the tubular member exceed a predetermined amount, which is determined by the spring 34, the valve 32 is unseated whereby water bypasses through the opening 31 and thence to the sprinkler conduit 19. By providing the pressure relief valve 32, the vane 26 oscillates at a controlled speed.

Referring now to Figs. 7, 8 and 9 of the drawings, I show another form of my invention which comprises a housing 10a separated by a vertical wall 11a into a water motor casing 12a and a casing 13a. Water is supplied to the casing 13a by a suitable hose connection 14a. Extending through the casing 12a is a sprinkler conduit 19a having a plurality of sprinkler orifices 24a therein. The sprinkler conduit 19a is secured to a suitable bearing sleeve member 58, as shown in Fig. 8. Secured to the sprinkler conduit 19a and adapted for pivotal movement therewith is a water motor vane 26a.

The wall 11a is provided with openings 59 and 61 at opposite sides of the vane 26a, as shown in Fig. 7. The casing 13a is covered by a suitable outer wall or cover plate 62, as shown. Also, the casing 13a is of a shape shown in Fig. 7 and is provided with an opening 63 which encircles the sprinkler conduit 19a and the openings 59 and 61, as shown. The opening 63 is provided with a lower portion in position to communicate with the hose connection 14a whereby water is introduced into the casing 13a.

Mounted for pivotal movement between the walls 62 and 11a of the casing 13a on a suitable pivot pin 64 is a valve plate member 66. As shown in Fig. 7, the casing 13a is provided with inwardly extending projections 67 and 68 adjacent opposite sides of the valve plate member 66 adjacent the opening 59. In like manner, the casing 13a is provided with inwardly extending projections 69 and 71 at opposite sides of the valve plate member 66 adjacent the opening 61. With the valve plate 66 in the position shown in solid lines in Fig. 7, opposite ends thereof engage the projections 67 and 71 whereby water entering the opening 63 passes through the opening 59 into the adjacent side of the casing 12a. As the water forces the vane 26a in a counter-clockwise direction, as viewed in Fig. 7, the water at the opposite side of the vane 26a flows out through the opening 61 into the casing 13a above the valve plate 66 and thence through the sprinkler conduit 19a to the sprinkling orifices 24a. On the other hand, when the valve plate member 66 is moved to the dotted line position, the water entering the casing 13a through the hose connection 14a enters the opening 61, thus forcing the valve plate 26a in a clockwise direction, as viewed in Fig. 7. Any water at the opposite side of the vane 26a is then exhausted through the opening 59 above the plate 66 to the sprinkler conduit 19a and then to the sprinkling orifices 24a.

The valve plate 66 is actuated by means now to be described. Secured to the valve plate 66 and projecting upwardly therefrom are a pair of arms 65 which are pivotally connected at their upper ends to parallel link members 68. The upper ends of the link members 68 are connected by a pin 75. Lateral movement of the links 68 is limited by a pair of stops 70 and 72 mounted on wall 11a at opposite sides of the links. Connecting the pins 75 and 64 is a spring 73a, as shown in Fig. 8.

Frictionally connected to the inlet end of the sprinkler conduit 19a within the casing 13a is an annular member 73 which has a cut-out portion 74 therein for receiving the upper end of the link 68 and the pin 75. Mounted on the sprinkler conduit 19a adjacent the annular member 73 is a second annular member 76 which has a cut-out portion 77. In view of the fact that the annular member 73 is frictionally connected to the conduit 19a, it may be rotated relative to the annular member 76, thereby

varying the size of the gap for receiving the pin 75 and the upper ends of the links 68.

From the foregoing description, the operation of my sprinkler shown in Figs. 7, 8 and 9 will be readily understood. Water is introduced through the hose connection 14a where it passes into the casing 13a and through the opening 59 beneath the valve plate 66 into the casing 12a. As the water passes into the casing 12a adjacent the opening 59, the vane 26a is pivoted in a counterclockwise direction, as viewed in Fig. 7. Counter-clockwise movement of the vane 26a causes corresponding movement of the sprinkler conduit 19a and the annular members 73 and 76 until the pin 75 engages the member 76. Upon engagement of the pin 75 by the member 76, the links 68 are moved about their pivotal connection to the arms 65 until this pivotal connection moves past dead-center of a line extending through the pins 64 and 75. The valve plate member 66 is then moved quickly, by the spring 73a, to the dotted line position shown in Fig. 7. In the dotted line position, the water entering the hose connection 14a passes through the opening 61 into the adjacent side of the casing 12a. Any water at the opposite side of casing 12a is exhausted through the opening 59 to the conduit 19a and thence to the sprinkling orifices 24a.

To vary the angular movement of the sprinkling conduit 19a, the annular member 73 is rotated relative to the annular member 76, whereby the gap between the members 73 and 76 can be varied. That is, by moving the member 73 in a counter-clockwise direction, the gap for receiving the pin 75 is increased whereas rotation of the member 73 in a clockwise direction decreases the gap, thus reducing the distance that the sprinkling conduit 19a moves.

The valve plate member 66 also serves as a pressure release valve to bypass water from the casing 13a to the conduit 19a when an excess pressure exists within the casing 13a. That is, when there is an excess water pressure within the casing 13a, the valve plate 66 will be forced away from the points 68 and 71, as the case may be, whereby a portion of the fluid passes directly to the sprinkler conduit 19a. The tension spring 73a serves as a means to actuate the valve plate member 66 instantaneously whereby there is no retarded movement of the sprinkler conduit 19a at each end of its travel, thus assuring proper distribution of the water.

Referring now to Figs. 10 and 11 of the drawings, I show another modification of my sprinkler. The sprinkler comprises a housing 10b separated by a partition wall 11b into a water motor casing 12b and a casing 13b for receiving water from a hose connection 14b. Extending through the water motor casing 12b is a sprinkler conduit 19b having a plurality of sprinkler orifices 24b therein for dispensing water. Secured to and mounted for pivotal movement with the sprinkler conduit 19b is a water motor vane 26b. Water is introduced into the casing 12b through a pair of angularly spaced openings 78 and 79. As shown in Fig. 11, the openings 78 and 79 are positioned at opposite sides of the water motor vane 26b. Communicating with and adapted for pivotal movement relative to the inlet end of the sprinkler conduit 19b is one end of an L-shaped conduit 81. The other end of the conduit 81 is adapted to be moved selectively into engagement with the openings 78 and 79 whereby water is exhausted through the conduit 81 to a sprinkler conduit 19b.

Mounted for pivotal movement adjacent the inlet end of the sprinkler conduit 19b within the casing 13b is one end of an outwardly extending arm 82. The other end 70 of the arm 82 extends inwardly as at 83 toward the partition wall 11b, as shown in Fig. 10. Pivotally connected adjacent the outer end of the conduit 81 is one end of a spring member 84. The other end of spring 84 is connected to the outer end of arm 82. The spring 84 is thus adapted to urge the arm 82 and conduit 81 in op-

posite directions when the pivotal connection between the spring 84 and the arm 82 passes dead-center of a line extending radially through the axial center of the conduit 19b and the pivotal connection between the spring 84 and the conduit 81. Suitable stop members 86 and 87 are provided at opposite sides of the arm 82 to limit angular movement thereof. Also, stop members 85 and 85a are provided at opposite sides of the conduit 81 to limit rotation thereof. Secured to the sprinkler conduit 19b adjacent the arm 82 is an actuating member 88 having a recess 89 therein defining shoulders 91 and 92 which are disposed to engage the inwardly extending portion 83 of the arm 82 upon rotation of the sprinkler conduit 19b.

Communicating with the inlet to the casing 13b adjacent the hose connection 14a is one end of a conduit 93. The other end of the conduit 93 is connected to a pressure relief valve 94 which may be in the form of a valve member 96 which is urged toward seated position by means of a spring 97. Communicating with the valve 94 is one end of a flexible conduit 98. The other end of the flexible conduit 98 is in communication with the sprinkler conduit 19b whereby the sprinkler conduit is adapted for free pivotal movement.

In operation, the water is introduced into the hose connection 14b into the casing 13b where it enters the exposed opening 78 or 79, as the case may be. With the apparatus in the position shown in Fig. 11, the water enters the water motor casing 12b through the opening 79 whereby the lower end of the vane 26b is moved toward the right, as viewed in Fig. 11. Any water in the casing 12b at the right side of the vane 26b, as viewed in Fig. 11, is then exhausted through the opening 78 and the L-shaped conduit 81 to the inlet end of the sprinkler conduit 19b whereupon the water passes out through the spray orifices 24b. As the water enters the opening 79, the sprinkler conduit 19b rotates in a counterclockwise direction and carries with it the actuating member 88. The shoulder 92 thus engages the inwardly extending portion 83 of the arm 82 and rotates the same in a counter-clockwise direction until the pivotal connection of the arm 82 and the spring 84 passes dead-center of a line extending radially from the axial center of the conduit 19b through the pivotal connection of the spring 84 to the L-shaped conduit 81. The conduit 81 is then moved quickly toward the left, as viewed in Fig. 11, into register with the opening 79. In this latter position, water is introduced into the casing 12b through the opening 78 and water at the opposite side of the vane 26 is exhausted through opening 79 and L-shaped conduit 81 to the sprinkler conduit 19b and the sprinkler orifices 24b. It will thus be seen that as the water is introduced alternately at opposite sides of the vane 26b, the vane and the sprinkler conduit 19b carried thereby is oscillated.

In Figs. 13 and 14, I show another form of my invention in which the pressure relief means is mounted in the vane 26c of a water motor. The exhaust of the water motor is operatively connected to a sprinkler conduit 19c whereby the sprinkler conduit is oscillated in the manner described above. The water motor is housed within a suitable housing 10c which is divided into a water motor casing 12c and a second casing 13c by a partition wall 11c. Water is introduced into the casing 13c by a suitable hose connection 14c. The pressure relief means comprises a pair of relief valves 99 and 101, as shown in Figs. 13 and 14. The pressure relief valve 99 is adapted to bypass water through the vane 26c when the vane is traveling in one direction and the pressure exceeds a predetermined amount. On the other hand, the pressure relief valve 101 is adapted to by-pass water and release pressure when the vane 26c is travelling in the opposite direction and the pressure exceeds a predetermined amount. The direction of flow of water through the pressure relief valves 99 and 101 is shown by arrows 102 and 103, respectively.

Referring now to Figs. 15 and 16, I show a still further modified form of my invention which comprises a housing 10d separated by a partition wall 11d into a water motor casing 12d and a second casing 13d. Water is introduced into the casing 13d by a suitable hose connection 14d. Mounted in the casing 12d for pivotal movement with a sprinkler conduit 19d is a water motor vane 26d.

Water is introduced alternately at opposite sides of the vane 26d through openings 104 and 106. Communicating with and adapted for pivotal movement relative to the inlet end of the sprinkler conduit 19d is one end of an L-shaped conduit 107. The other end of the L-shaped conduit 107 is adapted to register alternately with the openings 104 and 106 for exhausting water from the casing 12d at opposite sides of the vane 26d. Secured to the sprinkler conduit 19d adjacent the L-shaped conduit 107 is one end of an outwardly extending arm 108. Mounted for pivotal movement on the sprinkler conduit 19d adjacent the arm 108 is an actuating member 109 having a recess portion 111 defining shoulders 113 and 114 which are in position to engage an inwardly extending pin 116 carried by the L-shaped conduit 107, as shown in Fig. 15. Extending outwardly of the actuating member 109 are stop members 117 and 118 which are adapted to be engaged by opposite sides of the arm 108 as the arm is rotated in opposite directions. The lower end of the actuating member 109 has a cam surface 119 which is engaged by a cam follower 121. The cam follower is urged into engagement with the cam surface 119 by a compression spring 122. Suitable stops 120 and 120d are provided at opposite sides of the L-shaped conduit 107 to limit rotation thereof.

In operation, water is introduced into the casing 13d through the hose connection 14d where it flows into the exposed opening 104 or 106, as the case may be. With the apparatus in the position shown in Fig. 16, water is introduced through the opening 104 whereby the vane 26d is rotated in a counter-clockwise direction. As the vane rotates in a counter-clockwise direction, the arm 108 engages pin 118 and rotates the actuating member 109 until the apex of the cam surface 119 passes the cam follower 121. The shoulder 114 of the actuating member 109 then engages the pin 116 carried by the L-shaped conduit 107 whereupon the conduit 107 is moved quickly into engagement with the opening 104. The vane 26d is then moved in a clockwise direction until the arm 108 engages the pin 117 and moves the actuating member 109 whereby the cam follower 121 passes the apex of the cam surface 119 whereupon the shoulder 113 engages the pin 116 and returns the L-shaped conduit 107 into register with the opening 106. As water is introduced selectively into the openings 104 and 106 it is exhausted at the other side of the vane 26d through openings 106 and 104, respectively. That is, the water at the exhaust side of the vane 26d passes through the opening 104 or 106, as the case may be, into the L-shaped conduit 107 to the sprinkler conduit 19d and then to the sprinkler orifices 24d.

From the foregoing, it will be seen that I have devised an improved wave type sprinkler which operates at a predetermined speed and distributes the water evenly over the entire sprinkler pattern. By communicating the sprinkler conduit with the exhaust side of the water motor, in combination with pressure relief means for bypassing water into the sprinkler conduit when an excess water pressure is reached, the apparatus operates continuously at a controlled rate. Also, by providing means for adjusting the angular travel of the sprinkler conduit, the sprinkler pattern may be easily and quickly varied. Furthermore, my improved sprinkler apparatus comprises a minimum of parts and a minimum of maintenance to keep the same in efficient operating condition.

While I have shown my invention in several forms, it

will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. A sprinkler comprising a water motor having a vane mounted for pivotal movement in a casing and including a water inlet and a water outlet, a conduit operatively connected to said vane to oscillate therewith and having a water inlet in communication with the outlet of said water motor, there being at least one sprinkling opening in said conduit, and pressure relief means disposed to by-pass water to said conduit when the water pressure exceeds a predetermined amount, whereby the water motor oscillates at a predetermined speed.

2. A sprinkler as defined in claim 1 in which the pressure relief means comprises a pressure relief valve interposed between and in communication with the inlet for the water motor and said conduit.

3. A sprinkler as defined in claim 1 in which the pressure relief means comprises pressure relief valves in the vane of the water motor.

4. A sprinkler as defined in claim 1 in which the pressure relief means comprises a second casing in communication with the casing for the water motor and said conduit, and a pressure relief valve in said second casing to by-pass the water to said conduit when the water pressure exceeds a predetermined amount.

5. A sprinkler comprising a water motor having a vane mounted for pivotal movement in a casing and including a water inlet and a water outlet, a conduit connected to said vane to oscillate therewith and having a water inlet in communication with the outlet of said water motor, there being a plurality of sprinkling openings in said conduit, and pressure relief means disposed to by-pass water to said conduit when the water pressure exceeds a predetermined amount, whereby the water motor oscillates at a predetermined speed.

6. A sprinkler comprising a water motor casing having a vane mounted for pivotal movement therein, a conduit extending through said casing and adapted for pivotal movement relative thereto, means connecting said conduit to said vane whereby said vane moves with said conduit, there being at least one sprinkling opening in said conduit outwardly of said casing, means introducing water into said casing alternately at opposite sides of said vane whereby said vane is oscillated, means communicating said conduit with said casing alternately at the opposite side of said vane from the side that water is introduced whereby water is exhausted through said conduit, and pressure relief means disposed to by-pass water to said conduit when the water pressure exceeds a predetermined amount, whereby said vane oscillates at a predetermined speed.

7. A sprinkler comprising a water motor casing, a conduit extending through said casing and adapted for pivotal movement relative thereto, a water motor vane connected to said conduit within said casing and adapted for pivotal movement therewith, there being at least one sprinkling orifice in said conduit outwardly of said casing, there being openings in said conduit communicating with said casing at opposite sides of said vane, a tubular member telescoping within said conduit and having a water inlet at one end thereof and a water outlet at the other end thereof in communication with the end of said conduit carrying said sprinkling orifice, a transverse partition in said tubular member, a first pair of openings in said tubular member at opposite sides of said tubular member and at opposite sides of said partition from each other and adapted to be moved into alignment with the openings in said conduit upon relative rotation of said conduit and said tubular member in one direction whereby water entering said water inlet passes

through the adjacent one of said first pair of openings into said casing adjacent a first side of said vane and any water at the other side of said vane passes through the other one of said first pair of openings into said conduit to said sprinkling orifice, a second pair of openings in said tubular member spaced angularly from said first pair of openings and at opposite sides of said tubular member and at opposite sides of said partition from each other and adapted to be moved into alignment with the openings in said conduit upon relative rotation of said conduit and said tubular member in the other direction whereby water entering said water inlet passes through the adjacent one of said second pair of openings into said casing adjacent said other side of said vane and any water at said first side of said vane passes through the other one of said second pair of openings into said conduit to said sprinkling orifice, means introducing water into said water inlet, and pressure relief means disposed to by-pass water to said conduit when the water pressure exceeds a predetermined amount.

8. A sprinkler as defined in claim 7 in which the pressure relief means comprises a pressure relief valve in the transverse partition.

9. A sprinkler as defined in claim 7 in which the means introducing water into the water inlet comprises a second casing in communication with said water inlet.

10. A sprinkler as defined in claim 7 in which quick action means is provided for rotating said tubular member relative to said conduit when said conduit approaches the extreme limits of its travel in opposite directions.

11. A sprinkler as defined in claim 10 in which the quick action means comprises a first member secured to the tubular member and extending outwardly thereof, a second member mounted for pivotal movement on said tubular member and extending outwardly thereof, actuating means carried by said conduit and disposed to move said second member in response to pivotal movement of said conduit, means limiting pivotal movement of said conduit, and spring means connected at opposite ends to said first and second members and urging said first and second members in opposite directions upon the connection of said spring means to said second member passing dead-center of a radially extending line passing through the axial center of said tubular member and the connection of said spring means to said first member.

12. A sprinkler as defined in claim 11 in which the means limiting pivotal movement of said conduit comprises adjustable stop means at opposite sides of said first member whereby the angular pivotal movement of said conduit may be varied.

13. A sprinkler comprising a water motor casing, a conduit having an inlet at one end and an outlet at the other end thereof extending through said casing and adapted for pivotal movement relative thereto, a water motor vane connected to said conduit within said casing and adapted for pivotal movement therewith, there being at least one sprinkling orifice in the outlet of said conduit outwardly of said casing, a second casing in communication with the inlet of said conduit, there being passageways communicating said second casing with said water motor casing at opposite sides of said vane, valve means in said second casing introducing water through said passageways into said water motor casing alternately at opposite sides of said vane and exhausting water from the water motor casing to said conduit through said passageways which are opposite the ones thereof introducing water, and pressure relief means in said second casing adapted to by-pass water to said conduit when the water pressure exceeds a predetermined amount.

14. A sprinkler comprising a water motor casing, a conduit having an inlet at one end and an outlet at the other end thereof extending through said casing and adapted for pivotal movement relative thereto, a water motor vane connected to said conduit within said casing and adapted for pivotal movement therewith, there being

at least one sprinkling orifice in the outlet of said conduit outwardly of said casing, a second casing in communication with the inlet of said conduit, there being an inlet passageway in said second casing and other passageways communicating said second casing with said water motor casing at opposite sides of said vane, a valve plate mounted for pivotal movement in said second casing communicating said inlet passageway with said other passageways to said water motor casing alternately at opposite sides of said vane and communicating said conduit alternately with said other passageways which are opposite the ones thereof in communication with said inlet passageway, quick action means actuating said valve plate upon said conduit approaching the extreme limits of its travel in opposite directions, and pressure relief means disposed to by-pass water from said second casing to said conduit when the water pressure exceeds a predetermined amount.

15. A sprinkler as defined in claim 14 in which the second casing is provided with inwardly extending portions at opposite sides of the valve plate adjacent each end of said valve plate in position to be engaged by said valve plate to define a control and pressure relief valve between said second casing and said valve plate.

16. A sprinkler as defined in claim 14 in which the means actuating said valve plate comprises an arm member secured at one end to said valve plate adjacent the pivot point thereof with the other end thereof extending outwardly toward the conduit, a link pivotally connected at one end to said other end of said arm member, means limiting lateral movement of the other end of said link, spring means connecting said other end of the link to said valve plate adjacent the pivot point thereof, and means carried by the conduit disposed to engage said other end of the link upon pivotal movement of said conduit whereby said other end of the link passes dead center of a line passing through said pivot point of the valve plate and the pivotal connection of said link to said arm member when said conduit approaches the extreme limits of its travel in opposite directions.

17. A sprinkler as defined in claim 16 in which the means carried by the conduit comprises a stop member carried by said conduit and disposed to engage said other end of the link when the conduit is pivoted in one direction, a second stop member carried by said conduit and disposed to engage said other end of the link when the conduit is pivoted in the opposite direction, and means to vary the positions of said stop members relative to each other whereby the angular movement of said conduit can be varied.

18. A sprinkler comprising a water motor casing having a vane mounted for pivotal movement therein, a conduit extending through said water motor casing and adapted for pivotal movement relative thereto and including a water inlet adjacent one end thereof, means connecting said conduit to said vane whereby said vane moves with said conduit, there being at least one sprinkling orifice in said conduit outwardly of said casing, a second casing adjacent said water motor casing, there being passageways communicating said second casing with said

water motor casing at opposite sides of said vane, means introducing water into said second casing, means carried by said conduit communicating said conduit alternately with said passageways at opposite sides of said vane whereby water is exhausted through said conduit to said sprinkling orifice and pressure relief means disposed to by-pass water to said conduit when the water pressure exceeds a predetermined amount, whereby said vane oscillates at a predetermined speed.

19. A sprinkler as defined in claim 18 in which the means communicating the conduit alternately with the passageways at opposite sides of the vane comprises a second conduit connected at one end to the inlet of the first mentioned conduit and adapted for pivotal movement relative thereto with the other end of said second conduit adapted to communicate selectively with said passageways at opposite sides of the vane, an arm mounted for pivotal movement relative to said first mentioned conduit, means limiting angular movement of said arm, an actuating member mounted non-rotatably on said first mentioned conduit and disposed to engage said arm upon a predetermined amount of pivotal movement of said actuating member, and spring means connecting said second conduit to the free end of said arm and urging the same in opposite directions upon the connection of said spring means to said arm passing dead-center of a radially extending line passing through the axial center of said first mentioned conduit and the connection of said spring means to said second conduit.

20. A sprinkler as defined in claim 18 in which the means communicating the conduit alternately with the passageways at opposite sides of the vane comprises a second conduit connected at one end to the inlet of the first mentioned conduit and adapted for pivotal movement relative thereto with the other end of said second conduit adapted to communicate selectively with said passageways at opposite sides of the vane, means limiting pivotal movement of said second conduit, a cam member mounted for pivotal movement on said first mentioned conduit, a radially extending arm mounted non-rotatably on said first mentioned conduit, stop members carried by said cam member at opposite sides of said arm in position to be engaged by said arm upon a predetermined amount of pivotal movement of said first mentioned conduit, actuating means carried by said cam member and disposed to engage said second conduit and move the same selectively into communication with said passageways at opposite sides of the vane upon a predetermined amount of pivotal movement of said cam member in opposite directions, and a spring biased cam follower disposed to engage said cam and rotate the same in opposite directions upon a predetermined amount of rotation of said first conduit.
